UNITED STATES PATENT OFFICE.

WILLIAM W. BAGLEY, OF NEW YORK, N. Y.

TUBULAR RECEPTACLE.

971,958.

Specification of Letters Patent.

Patented Oct. 4, 1910.

Application filed March 12, 1910. Serial No. 548,828.

To all whom it may concern:

Be it known that I, WILLIAM W. BAGLEY, a citizen of the United States, and a resident of the city of New York, borough of 5 Manhattan, in the county and State of New York, have invented a new and Improved Tubular Receptacle, of which the following is a full, clear, and exact description.

The invention is an improvement in tubular receptacles, particularly those constructed of sheet metal, and has in view a receptacle embodying a tubular body portion, a tubular neck of reduced diameter and a conical or tapering portion connecting the body 10 portion to the neck, the receptacle being adapted to be economically produced in one piece from a blank.

Reference is to be had to the accompanying drawings forming a part of this specification, in which similar characters of reference indicate corresponding parts in all the views.

Figure 1 is a plan of a blank from which a receptacle embodying my invention is 25 adapted to be constructed; Fig. 2 is an outer face view of the blank, showing the first step in the construction of the tubular receptacle; Fig. 3 is a similar view, showing the second step in the construction; Fig. 4 is a 30 like view, showing the third and last step in the construction of the receptacle; Fig. 5 is a perspective view of a cap adapted to fit over the lower end of the receptacle; and Fig. 6 is a similar view of a cap adapted to fit over 35 the upper end of the receptacle.

The blank from which the preferred form of my invention is constructed, as shown in Fig. 1 comprises a body portion 5 having laterally-extending tabs 6 adjoining the 40 trapezoidal portions 7 extending from the upper edge of the body portion 5, and taking in the full width thereof, each trapezoidal portion having a rectangular or neck portion 8 at the top, which is shown to be 45 provided with a laterally-extending tab 9. Both the tabs 6 and tabs 9 are of slightly greater height or length than the portions to which they are joined, the tabs 6 extending slightly below the lower edge of the body 50 portion 5, and the tabs 9 extending a like distance above the top of the cap portions 8. In the construction of the receptacle from a blank of this form, the tabs 6 and 9 are first 55 folded inwardly on the dotted lines shown in Fig. 1, presenting the form shown in Fig. 2. The blank is then bent into cylindrical

form, with the tabs at the inside, the curving being in a direction to bring the edges of the two trapezoidal portions and their respective neck portions and tabs into opposed 60 position, presenting the cylindrical body shown in Fig. 3. The opposed edges of the separated portions at the top of the body are then forced inwardly together, forming the completed tubular receptacle, which is 65 shown to comprise the tubular body portion 10, the tubular neck portion 11, and the conical portion 12 connecting the body portion to the neck, the tabs 6 producing the extended tubes 13 and 14 respectively closely fitting 70 and extending from the body 10 and neck 11. The tube thus formed is provided with a joint 15 at one side extending throughout its length, and a joint 16 at the opposite side extending from the neck and conical or 75 tapering portion of the receptacle only. The reduced tubular portions 13 and 14 are adapted to receive caps 17 and 18 respectively, forming the bottom and top of the receptacle, these caps obviously forming 80 when in place, a finished joint with the body and neck of which they are of the same respective diameters.

Having thus described my invention, I claim as new and desire to secure by Letters 85 Patent:

1. A receptacle comprising a tubular body portion, a tubular neck of reduced diameter, and a tapering portion connecting the body and neck, the receptacle constructed of a 90 single piece of sheet material and having a joint at one side extending continuously through the body, tapering portion and neck, and having a joint at the opposite side extending through the neck and tapering portion only.

2. A receptacle comprising a tubular body portion, a tubular neck portion of reduced diameter, having a closely-fitting tubular portion extending thereabove, and a tapering portion connecting the body and neck, the receptacle constructed of a single piece of sheet material and having a joint at one side extending through the body, tapering portion, neck and the inner tubular portion 100 of the neck, and having a butt joint at the opposite side extending through the neck, the inner tubular portion of the neck and the tapering portion only.

3. A receptacle comprising a tubular body 110 portion, a tubular neck of reduced diameter, a tubular portion closely fitting within and

extending slightly beyond the neck, and a tapering portion connecting the body and neck, all constructed of a single piece of sheet material and having butt joints.

- 5 4. A receptacle comprising a tubular body portion, a tubular neck of reduced diameter, a tapering portion connecting the body and neck, tubular portions respectively closely fitting the body portion and neck portion and respectively extending a substantial distance to the outside of the body portion and neck portion, the receptacle constructed of a

single piece of sheet material, with the closely-fitting tubular portions respectively formed integral with and folded inwardly 15 from the abutting edges of the body portion and neck.

In testimony whereof I have signed my name to this specification in the presence of two subscribing witnesses.

WILLIAM W. BAGLEY.
